BLOW TORCHES

Alexander Scheenwald, Grove City, Pa., assignor to P. Wall Mfg. Company, Grove City, Pa., a corporation of Pennsylvania

Application July 17, 1956, Serial No. 598,415

2 Claims. (Cl. 158—33)

My invention relates to blow torches of the type wherein volatile fuels such as gasoline are supplied under pressure to a burner nozzle where they are atomized and mixed with air, for combustion.

One object of my invention is to provide a blow torch of the character referred to, wherein no priming and preheating is required in order to start combustion at the burner nozzle, and wherein provision is made for temporarily supplying air past the nozzle at pressure greater than the air pressure required for a normal flow of fuel to the nozzle, the supply of air for initial vaporization of the fuel being automatically cut off when the air pressure for feeding the fuel is at normal working pressure, after the flame has been started by a match or other lighter during the supply of high pressure air for vaporization.

Another object of my invention is to provide means in a blow torch for preheating the supply of fuel during its flow to the burner nozzle.

The single figure of the accompanying drawing is a cross sectional view through a blow torch that embodies my inventive features.

The numeral 2 represents a fuel tank of conventional form having a filling cap 3, an air inlet 4 from a suitable source of air under pressure, and a pipe 5 through which fuel is discharged by air pressure entrapped in the upper portion of the tank 2.

My invention includes a burner body 7 having an improved arrangement of passageways and control devices whereby the foregoing objects are obtained. The body has suitably secured thereto a burner tube 8 that is provided with a suitable number of openings 9 through which will be drawn air for combustion in the tube during normal operation of the torch. The valve block or body has a passageway 10 therein which communicates past a valve 11 with a passageway 12 that, in turn, communicates with the space between an air-mixing nozzle 13 which is concentric with a fuel nozzle 14 that is controlled by the usual fuel valve and its stem 15.

When air under perhaps 25 p. s. i. is supplied into the tank and through the passages 10 and 12 to the air-mixing nozzle 13, fuel also is being supplied into the nozzle 14 at that time, from the feed pipe 5, through a coil 16 and a line 17 into the nozzle 14. The fuel will be atomized and vaporized by the high-pressure air, to permit of it being ignited at the nozzle 13 as by a flame or an electrical ignition coil inserted through one of the openings 9.

The valve 15 will then be adjusted to a desired working position, and the supply of air through the line 10 will be cut off as hereinafter explained.

2

Since air pressure considerably higher than working pressure is required for effecting atomization to a point at which the ignition can be secured without preheating or priming, I use the valve 11 for automatically cutting off the flow of air through the passageways 10 and 12 when pressure in the line 4 is reduced to a degree suitable for normal operation. This pressure may be in the neighborhood of 15 lbs. per square inch or some other pressure lower than the atomizing pressure above mentioned.

The valve 11 is held to its seat by a coil spring 19, the expansive force of which is adjusted by a knob 20 that has screw-threaded engagement with the wall of the burner body 7. As indicated above, the starting pressure will be perhaps 25 lbs. p. s. i., which will be sufficient to push the valve 11 from its seat and allow flow of air to the air-mixing nozzle. When ignition has been effected, the pressure of air in the line 4 will be reduced to a point at which the valve 11 will be closed by its spring, but the pressure will be sufficient to secure the desired rate of fuel flow, from the discharge tube 5, for mixing with air in the burner tube 8. The fuel passes through the coil 16 where it is preheated and therefore will produce greater combustion efficiency in the burner tube.

I claim as my invention:

1. A blow torch apparatus that comprises in combination with a fuel tank which has means for directing air into it under pressure and has a discharge pipe therein leading upwardly from the bottom thereof, of a burner body, a forwardly-extending burner tube carried thereby and having air inlet openings intermediate its ends, a fuel nozzle having a passageway, that extends into the rear end of the tube, a heating coil in the tube and communicating at one end with the said pipe and at its other end with said passageway, a valve that controls fuel flow from the passageway, a second passageway that conducts air from the upper end of the fuel tank to the fuel nozzle through a third passageway that is concentric to the first-named passageway, and a pressure-actuated valve in the second-named passageway that is opened by the air pressure in the upper part of the tank when such pressure exceeds a predetermined degree, and is automatically closed and shuts off air flow through this second passageway, when the pressure falls below said degree, discharge of air from the third-named passageway and the fuel from the first-named passageway being in the same general direction.

2. Torch apparatus as recited in claim 1, wherein discharge from the last-named passageway is into an air mixing nozzle which is open into the burner tube, at its forward side.
